UNITED STATES PATENT OFFICE

ALFRED F. MCCOLLUM, OF BLOOMSBURG, PENNSYLVANIA, ASSIGNOR TO THE MAGEE CARPET CO., OF BLOOMSBURG, PENNSYLVANIA, A CORPORATION OF PENNSYLVANIA

PRINTED PILE FABRIC

Application filed December 19, 1927. Serial No. 241,082.

This invention relates to improvements in printed pile fabrics, and has a particularly valuable application to the printing of rugs and carpets.

5 The principal object of the invention is to provide simple and highly efficient means for printing pile fabrics that will afford a printed design that will have to a greater degree than is obtainable by prior methods the desirable characteristics of a woven design.

To this end the invention contemplates the provision of printing means of novel form capable of printing a design on pile fabrics uniformly colored throughout and entirely 15 free from unevenness of texture; in which the dye substance extends completely to the bottom of the pile if desired; and having a sharp and clearly defined outline which extends straight down through the pile on a plane 20 substantially perpendicular to the base of the fabric.

More specifically, the invention contemplates the provision of a novel form of printing element adapted for the printing of pile fabrics with the desirable results specified above.

The invention further resides in the provision of a finished product in the form of a printed pile fabric in which the printed design compares favorably as outlined above with the product of a jacquard machine.

In the attached drawings:

Fig. 1 is a face view of a printing element made in accordance with my invention;

35 Fig. 2 is a fragmentary enlargement showing the details of one of the active printing areas;

Fig. 3 is a section on the line 3—3, Fig. 2;

40 Figs. 4 and 5 are fragmentary enlargements similar to that of Fig. 2 illustrating modifications within the scope of the invention;

Fig. 6 is a face view of a pile fabric printed in accordance with the present invention, and

45 Fig. 7 is a section on the line 7—7, Fig. 6.

With reference to the drawings, the printing element which constitutes a part of the present invention and which in the illustrated embodiment takes the form of a block may 50 have one or more elevated effective printing

areas conforming in shape to the design which it is desired to impose upon the pile fabric. In Fig. 1 for example, I have illustrated a block 1 in which these elevated printing surfaces 2 take the form of uniformly spaced rectangles. The depth of these elevated sections will depend to some extent upon the depth of the pile, but for all ordinary purposes, a depth of $\frac{1}{16}$ of an inch will be found satisfactory.

A face view of one of these effective printing areas 2 is shown in Fig. 2, and as clearly illustrated in this figure and in the sectional view of Figure 3, the surface of this section is broken up into a series of relatively small pyramidal projections, these small pyramids being distributed uniformly over the entire surface. It will further be noted by reference particularly to Fig. 3, that this printing surface is bounded by a continuous and clearly defined wall 3 which preferably and as shown is so formed as to present at the top a relatively sharp or knife edge which also in a preferred embodiment projects slightly above the tops of the pyramids. While the height of the pyramids will vary to some extent according to the depth of the pile with which the block is to be used, a height of $\frac{1}{16}$ of an inch with approximately sixty-four of the pyramidal projections per square inch so of surface will be found suitable for all ordinary depths of pile. The height of the projections and their number per unit surface area, however, may be varied considerably as the requirements demand.

A printing surface constituted as described above has been found highly desirable in the printing of pile fabrics and is of prime importance in the block-printing of fabrics having a pile of considerable depth. In fact, my invention has made practicable the printing by this method of long pile fabrics, the resulting printed product being characterized by a clean cut appearance and durability of design not readily produced even in low pile fabrics by the prior methods. The pyramidal recessed face is capable of penetrating the pile to any desired extent, and the dye held in the recesses and confined by the boundary wall 3 is deposited in quantities suffi-

cient to thoroughly saturate the entire pile and even the base warp if desired. Further, the distribution of the dyestuff is practically uniform so that the printed areas are 5 entirely free from unevenness and irregularities of color, and in this respect the patterns compare favorably with the woven designs produced on the jacquard and like machines. Also the knife edged boundary wall 3 so 10 restricts the flow of dye at the edges of the block as to give a clear definition at the edges of the printed design comparing favorably with that obtainable by any of the known and more expensive weaving methods and 15 which like the latter extend in a clearly defined plane substantially perpendicular to the base fabric from the top of the pile to the bottom. By means of this block, therefore, I have found it possible to provide a 20 printed rug having an entirely clear cut and finely defined design and in which each individual pile thread or tuft is uniformly colored throughout its length, and in which the colored areas are entirely uniform. I have, 25 therefore, provided by the aforescribed procedure a pile fabric having all the desirable characteristics of the more expensive article formed on the jacquard machine and which is even superior to the jacquard product by reason of the fact that the vehicle of 30 the dye, which may be starch, flour or similar material, flowing to the extreme base of the pile and even into the base warp expands the yarn both of the pile and base, and by 35 this expansion as well as by the adhesive properties inherent in the vehicle binds the pile threads in the base and gives an added strength and durability not obtainable in the other type of product.

40 While the pyramidal surface described above is preferred, it will be understood that any type of uniformly rough or recessed surface surrounded by a continuous bounding wall higher than the surrounding surfaces 45 may be used with some degree of success in the practice of this invention, since with the elevated boundary wall to penetrate the pile and to restrict the flow of the dye into the fabric, many different forms of roughened 50 surface will be sufficient to afford a practically uniform distribution of the dye and to eliminate the streaky effects resulting from the use of plain-faced type. It will be understood that the small projections from the 55 printing surface function not only to penetrate the pile, but also to maintain a uniform distribution of the dyestuff essential to a uniformly colored surface.

In Figs. 4 and 5, for example, I have illustrated other forms of surface which may be used in the practice of my invention. In Fig. 4, the surface is broken up by uniformly distributed circular recesses, and it will be noted also that in this instance as well as in 65 the form of face illustrated in Fig. 5, the

upper edge of this boundary line is not sharp and knife edged as is ordinarily preferred, but is of an appreciable width. Also in this instance, the bounding edge does not project above the surface in which the recesses are formed; and the edge is of stepped formation affording a design more closely resembling at the edges the effect obtained in a woven pattern. In Fig. 5, the surface is broken up by a series of longitudinal grooves.

70 A printing element having the characteristics of that described above may be made of wood, lacquered or otherwise rendered proof against absorption of the dyestuff, or any substance of sufficient hardness and not affected by the dye. Particularly desirable results have been obtained with aluminum, and other metals may be used.

75 Many other types of surface may be employed, although the form illustrated in Figs. 2 and 3 has been found particularly desirable and is preferred.

80 I claim:

85 As a new article of manufacture, a printed pile fabric in which the printed design is sharply defined at the edges by a plane substantially perpendicular to the base of the fabric and passing through the line that defines the design on the face of the pile, and 90 in which the pile threads are securely united with the base warps by the adhesive vehicle 95 of the printing medium.
